FIRE EXTINGUISHING

Frank H. Steinicke, Elmira, N. Y., assignor to
American-La France and Foamite Corporation,
a corporation of New York

Application January 16, 1932, Serial No. 586,996

4 Claims. (Cl. 169—11)

The invention relates to the use of compressed or liquefied gases, such as liquid CO₂ for extinguishing fires, and the object is to promote the rapidity of the extinguishing process by increasing the rate of dilution, with the extinguishing gas, of the atmosphere surrounding the burning object, to the end that such atmosphere may quickly become non-supporting of combustion. More especially the invention relates to the protection against fire damage of electrical apparatus, the purpose being to suppress quickly and effectively the combustion of the insulation, oil, etc. going on inside of the casing or enclosing shell of the apparatus. For this purpose the invention, as hereinafter described in greater detail, makes use of the simultaneous application of suction and pressure to the chamber in which the electrical or other apparatus is housed, thereby accomplishing prompt exchange of the normal atmosphere for an atmosphere which does not support combustion. The combined action of suction and pressure produces practically instantaneous dilution of the internal atmosphere and quick extinction of the fire, thereby greatly reducing the extent of fire damage, particularly in electric machines where this invention has its principal application and where such damage very quickly attains serious proportions.

The principle, susceptible of embodiment in various ways, is herein applied as exemplified in the accompanying drawing, representing a known type of motor generator set having the invention applied.

In this drawing the internal electrical and mechanical structure is represented generally by the numeral 1 being enclosed in a surrounding casing or shell represented by numeral 2 and which more or less completely surrounds the internal mechanism. The nature and detail of this apparatus is not of consequence to the present invention; in certain electrical apparatus the casing will normally contain an atmosphere of hydrogen gas used for cooling the windings, although generally the internal atmosphere will be air only.

The application of this invention to the apparatus illustrated involves the provision of an escape outlet 3 leading from the machine casing to some suitable place of discharge. In the case of hydrogen-cooled apparatus this outlet can be normally closed by an easily rupturable membrane indicated at 4, which is sufficient to confine the hydrogen normally against escape. In or associated with the outlet 3 there is a nozzle 5 adapted to discharge a fluid under high velocity, outwardly through the outlet 3 or in such way as

to produce an outward suction flow of the internal atmosphere therethrough on the ejector principle. This nozzle 5 can be connected to any suitable pressure source, but is desirably connected, as by pipe 6, to the source 7 of the liquefied gas used for the extinguishing medium, because in this way the nozzle becomes active instantly on the release of the extinguishing medium. The force of the discharging gas ruptures the thin membrane and thus opens the escape passage so that the normal internal atmosphere of the machine can pass out.

Simultaneously with the action of the suction-producing nozzle 5, the main branch 8 from the source 7 delivers extinguishing gas into the casing under pressure and at one or more points therein, according to the design of the machine and more or less remote from the ejector outlet or outlets, so that the normal internal atmosphere of the machine is promptly substituted by the extinguishing gas. In the case in hand, only one inlet discharge nozzle 9, is indicated. The extinguishing medium is necessary to be delivered at high pressure in order to produce a sufficiently prompt substitution of atmospheres and is preferably liquid CO₂ contained in one or more flasks or cylinders as indicated, and which may be arranged to discharge into the chamber of the machine continuously or at intervals as conditions may require. Apparatus suitable for this purpose is known in the art and is commonly organized for automatic operation, continuously or intermittently as stated, by means which constitute no part of the present invention and therefore omitted from the drawing.

The gas outlets 5 and 9 which discharge simultaneously are co-related, as to the sizes of their discharge orifices, so as to maintain a slightly positive pressure inside the machine during their action, enough to prevent possible infiltration of air from the outside, but yet at not so great a pressure as to endanger the casing. This is a matter which obviously depends upon the size and configuration of the machine casing or space and will readily be adjusted accordingly. Where the machine normally runs in a hydrogen atmosphere, it is obviously desirable to displace that gas with CO₂ gas as promptly as possible and to remove the hydrogen on discharge to some place where it is not likely to result in explosion, for which purpose the outlet 3, as stated, may run to the roof or some remote point of discharge. When the hydrogen has been removed and its place occupied by the CO₂ the need for the suction effect will have ceased and the nozzle 5 may be then discontinued as by closing the shut-off

valve 10 or by closing the outlet 3 with a suitable valve.

The invention is claimed as follows:

1. A fire protection system for apparatus in an enclosed space, comprising a normally closed escape passage for the normal atmosphere in said space, a source of compressed gas having an outlet for compressed gas associated with and adapted, when active, to apply the energy of the gas to open said escape passage, another outlet from said source adapted to deliver extinguishing gas into said space and means for rendering both outlets coincidentally active.

15 2. A fire protection system comprising in combination with a chamber enclosing the risk, a supply of liquefied CO₂, a system of discharge pipes for the CO₂ comprising a pipe terminating so as to discharge into said chamber and another pipe terminating so as to discharge in suction-
20 producing relation to the chamber and a single

control means for rendering said discharges operative coincidentally.

3. The method of protecting and extinguishing fires in closed chambers normally containing an atmosphere of air or combustible gas, which consists in maintaining a source of supply of fire extinguishing gas confined under pressure and in time of fire in said chamber discharging the gas into the same while coincidentally releasing a portion of said gas in suction-producing relation to the chamber, the gas pressure being such as to thereby effect a rapid exhaustion of the normal atmosphere in said chamber and substitution of said gas.

15 4. The method as set forth in the preceding claim in which the respective discharge and release of the gas are correlated to maintain a positive pressure within the chamber.
